UNITED STATES PATENT OFFICE.

SILAS M. FORD, OF ST. PAUL, MINNESOTA.

LATH-BOARD.

1,160,271.

Specification of Letters Patent.

Patented Nov. 16, 1915.

Application filed August 9, 1915. Serial No. 44,510.

To all whom it may concern:

Be it known that I, SILAS M. FORD, a citizen of the United States, residing at St. Paul, in the county of Ramsey and State of Minnesota, have invented certain new and useful Improvements in Lath-Boards, of which the following is a specification.

My invention relates to improvements in lath-boards adapted to be secured upon the 10 studding or beams of buildings to form a foundation for plaster.

The invention has for its object to provide a lath board of flexible fibrous sheeting which is corrugated to form keyed lath-like 15 projections and alternate depressions in order to receive the plaster in the depressions and to form hollow air spaces beneath the projections, and wherein the side edges of the projections are externally fractured so as to afford an irregularly broken and ragged surface for the plaster to cling to, thereby strengthening the plaster surface 20 and making it possible to increase the spaces between the lath projections.

25 More particularly the invention consists in the construction, combination, and arrangement of parts hereinafter described and claimed.

In the accompanying drawings showing 30 an embodiment of the invention, Figure 1 is a perspective view of a fragment of the improved lath-board held to form by an adherent backing sheet; Fig. 2 is a perspective view of a small fragment of the same upon 35 an enlarged scale to show the nature of the fractured edges; and Fig. 3 is a perspective view of a fragment of the board secured to the backing sheet by staples.

The lath-board of the present invention 40 is made preferably of rather thick waterproofed paper or board such as rope stock surfaced or impregnated with asphalt or the like, and stiff enough to break or crack exteriorly at the edges when bent and 45 pressed at a sharp angle.

The sheet is pressed or molded to form 50 corrugations having spaced lath-like projections 2 and alternate depressions 3, the projections on one side forming the depressions on the other side, and vice versa.

As will be seen from the drawings, the 55 sheet is pressed so that the projections are of keyed-lath shape with their undersides 4 bent inwardly toward each other at an angle sharp or small enough to cause the side edges 5 of the projections to be externally

fractured when the board is bent and pressed, that is for the exterior layers of the sheet to be fractured, so as to form ragged partially split side edges to which 60 the plaster will adhere with great tenacity. If desired the board can be first scored or lightly cut along the line of fold to cause it to break more readily. By reason of the greater adherence of the plaster to the fractured edges the projections can be spaced 65 far enough apart to allow the plaster to fill or nearly fill the depressions 3 beneath the inclined sides of the projections. The spaces between the faces of the projections and 70 their inwardly inclined undersides form longitudinal air spaces which serve as heat insulating and sound deadening spaces.

In order to hold the corrugations to form, 75 a backing sheet or board 6, preferably of waterproofed material, may be placed upon the back or underside of the corrugated sheet and made to adhere to it by asphalt or other suitable binding means, as shown in Fig. 1, or be fastened to it by means of 80 staples or other fastening devices 7 piercing the depressed portions of the corrugated sheet and the backing, as shown in Fig. 3.

In use the board can be made in a long 85 sheet of convenient width from which suitable lengths or sections can be cut off and nailed to the studding. When the board is in place and plastered over, the plaster will fill the keyed lath shaped depressions 3 between and under the lath projections 90 and adhere to the fractured edges of the projections while under each lath face will be a heat and sound insulating space. Furthermore the corrugations are flexible and 95 elastic enough to yield when the plaster expands under changes in humidity or temperature so that the plaster is less likely to shrink away from the lath board.

I claim:

1. A lath-board comprising a sheet of 100 flexible fibrous material corrugated to form interspaced keyed lath projections and intermediate depressions, the side edges of the projections being exteriorly fractured along their length to form an irregular holding surface for plaster.

2. A lath-board comprising a sheet of 110 flexible fibrous material corrugated to form interspaced keyed lath projections and intermediate depressions, the side edges of said projections being exteriorly fractured along their length to form an irregular

ragged holding surface for plaster, and means for holding said corrugations to form.

3. A lath-board comprising a sheet of flexible fibrous material corrugated to form interspaced lath projections and intermediate depressions, the under sides of said lath projections being bent inwardly toward each other and the side edges of said projections being exteriorly fractured along their length to form an irregular holding surface for plaster.

4. A lath-board comprising a sheet of flexible fibrous material corrugated to form

interspaced keyed lath projections and intermediate depressions, the side edges of the projections being exteriorly fractured along their length to form an irregular holding surface for plaster, and a backing sheet secured upon the underside of said corrugations whereby to hold them to form. 15 20

In testimony whereof I affix my signature in presence of two witnesses.

SILAS M. FORD.

Witnesses:

ARTHUR P. LOTHROP,
H. SWANSON.
